Inventor:
Daniel R. Scholes
By G. A. Graffatty.

UNITED STATES PATENT OFFICE.

DANIEL R. SCHOLES, OF CHICAGO, ILLINOIS, ASSIGNOR TO AERMOTOR COMPANY, OF CHICAGO, ILLINOIS, A CORPORATION OF ILLINOIS.

GEAR CASING.

Application filed December 1, 1921. Serial No. 519,148.

To all whom it may concern:

Be it known that I, DANIEL R. SCHOLES, a citizen of the United States, residing at Chicago, in the county of Cook and State of Illinois, have invented a certain new and useful Improvement in Gear Casings, of which the following is a full, clear, concise, and exact description.

My invention relates to gear casings and is of particular service when employed in connection with the gear casing disclosed in United States Letters Patent 1,141,356, issued June 1, 1915 to LaVerne Noyes. The gear casing disclosed in this patent is especially adapted to the housing of the power transmitting gearing of windmills. It is made in part of a hood or cover formed of a single sheet of metal supplemented by an inner flange at the base thereof to form a circumscribing groove for receiving the rim of a lubricant containing basin or casing base portion which, in conjunction with the hood, completely incloses the gearing.

It has been observed that the thin and flexible sheet metal of which the hood is made is usually of wavy or irregular contour at its base, where it rests upon the rim of the opening in the top of the base portion of the casing. I overcome this objection by means of a frame that is rigid in relation to the sheet metal and is preferably surrounded by the base of the hood to bring the frame into expanding relation to the hood base. The hood, being preferably upwardly tapering, effectively co-operates with said frame to efface the waves of the sheet metal of the hood. As this frame conforms in contour to the rim of the base portion of the gear casing, it forces the base portion of the hood similarly to conform.

In the preferred embodiment of the invention the frame is shaped in cross section in the form of an inverted U that furnishes the groove at the base of the hood which receives the rim of the base portion of the casing.

I will explain my invention more fully by reference to the accompanying drawings in which Fig. 1 is a vertical sectional view illustrating the preferred form of my gear

tasing as applied to windmills, the gearing being absent; Fig. 2 is a side view with parts broken away; Fig. 3 is a sectional view on line 3—3 of Fig. 1; Fig. 4 is an enlargement of parts of the sectional view of Fig. 1; Fig. 5 is a perspective view of the base portion of the hood and its strengthening frame in separated relation; Fig. 6 is a perspective view illustrating the elements of Fig. 5 in assembly; and Fig. 7 illustrates a sheet metal blank from which the form of hood shown may be made.

Like parts are indicated by similar characters of reference throughout the different figures.

The portion of the wind mill structure shown includes the top portion of a tower that terminates in a stationary upright tubular column 1 whose reduced upper end constitutes an upright shaft affording an upright axis about which the wind mill head 2 may turn upon a step bearing ring 3 supported upon the lower column portion. The head 2 is enlarged into an oil chamber or basin 4, constituting the preferred form of base portion of the casing, and may contain lubricant for the gearing of the mill. The head 2 carries an upright stirrup 5 whose parallel branches constitute upright guides that are simultaneously received in a grooved antifriction wheel. The threaded stem 5 of the stirrup 6 passes through the top of the hood 7 and a nut 8 is screwed down upon the top of the hood whereby the hood is thoroughly clamped in position.

The contour of the bottom of the hood substantially defines a parallelogram as does the contour at the top of the hood, the diagonal axes of the top of the hood intersecting at the axis of the tubular column 1 and being substantially perpendicular to the sides of the geometrical figure at the bottom of the hood. The hood is formed with eight triangular faces each of four of which being defined by the sides of the parallelogrammatic figure defined by the contour of the top of the hood and the respectively underlying corners of the parallelogrammatic figure defined by the contour of the bottom of the hood, while the remaining

100

four faces are defined by the sides of the parallelogrammatic figure defined by the contour of the bottom of the hood and the respectively overlying corners of the parallelogrammatic figure defined by the contour of the top of the hood. By the formation of the hood described there are afforded two triangular side walls or faces of the hood which are substantially parallel with each other and substantially parallel with 10 the planes of movement of the pitmen but taper slightly upwardly for the purpose of my invention, these walls and the remaining six walls or faces of the hood being brought 15 into very close proximity with the power transmitting mechanism carried upon the head of the windmill.

As illustrated, the opening at the top of the casing base portion 4 is oblong and the 20 opening at the base of the hood is correspondingly shaped.

In the process of manufacturing the hood a stamping of thin flexible sheet metal is desirably made in the form illustrated in 25 Fig. 7, this stamping including two extensions 9 that are folded into interlocking engagement, in the formation of the hood, to constitute a seam with the interlocking formation illustrated. The upper end of the 30 stamping terminates in four triangular wings 10 whose apex portions are provided with circular openings 11 that are brought into register when the stamping is folded, to receive the bolt 6, the wings 10 then 35 jointly serving to form the top wall of the hood.

As will be observed from the aforesaid patent to LaVerne Noyes, a circumscribing groove is provided at the base of the hood 40 by means of a single ribbon of sheet metal that is as flexible as the balance of the hood. The base of the hood and this ribbon, by reason of the flexible character of the sheet metal, are both apt to be wavy or irregular 45 in contour to make it difficult to fit the groove and the base portion of the gear casing. In carrying out my invention I employ a frame 12 that is shaped, in cross section, in the form of an inverted U. The groove 13 50 between the sides of the frame is oblong to conform in contour to and receive the oblong rim 14 that surrounds the opening in the top of the casing portion 4. The amount of sheet metal at the base of the hood is 55 such that it may be forced to conform in extent and contour to the exterior of the frame, it being understood that the base of the hood is made to conform as closely as possible to the frame before the frame and hood 60 are assembled. As the hood tapers upwardly the frame and the base of the hood have wedging engagement, and as the frame is rigid in relation to the sheet metal such frame is in expanding relation to the hood

base whereby the irregularities in the sheet 65 metal at the base of the hood are smoothed out to effect exact conformity between the same and the base of the hood. After the expanding action of the frame and hood has been carried to the desired extent, these elements are brought into permanent assembly 70 as by means of spot welding, the hood and frame being made of metal that permits of this method of their assembly.

As illustrated in the drawings, the base of 75 the hood, the frame 14 and the rim around the opening at the top of the base portion of the casing are oblong to permit of the sweep of the pitmen within the gear casing as is set forth in the aforesaid patent. It has been 80 found that the sheet metal of the hood is apt to be more wavy along the long sides of the oblong. By sloping one end wall 15 of the hood to a greater degree than the other walls thereof the wedging action between the hood 85 and the frame is increased more effectively to smooth the metal of the hood.

While I have herein shown and particularly described the preferred embodiment of my invention I do not wish to be limited to 90 the precise details of construction shown as changes may readily be made without departing from the spirit of my invention, but having thus described my invention I claim as new and desire to secure by Letters Pat- 95 ent the following:—

1. A gear casing including a base portion open at its top; a hood formed of flexible sheet metal; and a frame shaped in cross section in the form of an inverted U and 100 receiving the rim of said base portion of the casing in the groove thereof and assembled with and surrounded by the base of the hood, said frame being rigid in relation to the sheet metal of the hood and in expanding relation to the hood base.

2. A gear casing including a base portion open at its top; an upwardly tapering hood formed of flexible sheet metal; and a frame shaped in cross section in the form of an inverted U and receiving the rim of said base portion of the casing in the groove thereof and assembled with and surrounded by the base of the hood, said frame being rigid in 110 relation to the sheet metal of the hood and in expanding relation to the hood base.

3. A gear casing including a base portion having an oblong opening at its top; a hood formed of flexible sheet metal; an oblong base conforming in contour to said oblong 12 opening, said hood having a narrow side tapering upwardly; and an oblong frame conforming to said opening and the base portion of the hood and shaped in cross section in the form of an inverted U and receiving the rim of said base portion of the casing in the groove thereof and assembled 13 with and surrounded by the base of the

hood, said frame being rigid in relation to the sheet metal of the hood and in expanding relation to the hood base.

4. A gear casing including a base portion having an opening therein formed with a surrounding rim; a frame U-shaped in cross section and having its groove conforming to and receiving said rim; and a hood of sheet

metal with respect to which said frame is rigid and which hood and frame are assembled at the base of the hood.

In witness whereof, I hereunto subscribe my name this 16th day of November A. D., 1921.

DANIEL R. SCHOLES.
